UNITED STATES PATENT OFFICE.

RALPH P. TOWARD, OF RUSSELLTON, PENNSYLVANIA.

COUPLING FOR PIT-CARS.

1,250,390.

Specification of Letters Patent. Patented Dec. 18, 1917.

Application filed May 8, 1917. Serial No. 167,305.

To all whom it may concern:

Be it known that I, RALPH P. TOWARD, a citizen of the United States of America, residing at Russellton, county of Allegheny, and State of Pennsylvania, have invented certain new and useful Improvements in Couplings for Pit-Cars, of which the following is a specification.

This invention relates to couplers for pit cars and has for its object to provide a coupler for such purpose, in a manner as hereinafter set forth, having means in a manner as hereinafter referred to, whereby the coupling link carried by the rear sill of a forward car can be automatically coupled to and maintained in coupling position with the front sill of the rear car.

Further objects of the invention are to provide a coupler for the purpose set forth which is simple in its construction and arrangement, strong, durable, efficient in its use, automatic in its action, and comparatively inexpensive to manufacture.

With the foregoing and other objects in view the invention consists of the novel construction, combination and arrangement of parts, as hereinafter more specifically described and illustrated in the accompanying drawing, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a top plan view of a pair of pit cars showing the adaptation therewith of a coupler in accordance with this invention.

Fig. 2 is a section on line II-II, Fig. 1.

Fig. 3 is a front elevation of a pit car showing the adaptation therewith of the coupler link coupling device.

Fig. 4 is an inverted plan view of the device shown in Fig. 1 with a part of one car broken away.

Fig. 5 is a detail view of the locking pin and rock shaft.

Referring to the drawings in detail 1 and 2 denote a pair of pit cars. The car 1 has a front sill 3 and the car 2 has a rear sill 4.

The reference character 5 denotes the draw bar of each of the cars and said bar is disposed longitudinally, as well as centrally, of the bottom of the car and extends from the front sill 3 to the rear sill 4.

Associated with the rear end of the draw bar 5, is what may be termed an upper draw bar consisting of a longitudinally extending portion 6, a vertically extending portion 7, and a longitudinally extending portion 8. The portion 6 is fixedly secured to the draw bar 5 by the securing devices 9 and the portion 8 is positioned above and spaced from the draw bar 5 through the medium of the vertically extending portion 7.

The portion 8 in connection with the rear end of the draw bar 5, forms a recess 10 in which is positioned one end of the coupling link 11. Extending down through the portion 8 and through the draw bar 5, is a coupling pin 12, the latter has its ends upset as at 13, whereby the pin 12 is permanently secured to the portion 8 and rear end of the draw bar 5. The pin 12 permanently connects the coupling link 11 to the rear end of the car and when the link is not in use it can be shifted to seat upon the sill 4.

The front end of the draw bar has an elongated longitudinally extending slot 14 and associated with the front end of the draw bar 5 is what may be termed an upper draw bar consisting of a longitudinally extending portion 15, and an upwardly extending portion 16 which is curved forward and an elongated longitudinally extending portion 17 which is arranged over and spaced from the front end of the draw bar 5 thereby providing a recess 18.

The longitudinally extending portion 15 is fixedly secured to the draw bar 5 by securing devices 19 and said vertical portion 16 maintains the longitudinal portion 17 in spaced relation with respect to the front end of the draw bar.

The longitudinally extending portion 17 is provided with a longitudinally extending elongated slot 20 which is arranged in parallelism with the slot 14.

5 The bottom 21 and sill 4 has an opening for the passage of the pin 12. The sill 3 and bottom 21 has an elongated longitudinal slot which alines with the slots 14 and 20.

Depending from the sill 3 is a pair of 10 brackets 22, 23, having openings 24 for passage of a lubricant if desired.

Mounted in said brackets is a rock shaft 25, of a length greater than the length of the sill 3, and each end of said rock shaft 25 15 is upturned as at 26, and provided with counterweight 27.

The rock shaft 25 at its center has a depending arm 28 which carries a counter-weight 29 and said rock shaft 25, at its center, is 20 furthermore provided with a vertically disposed locking pin 30 having a forward projecting lug 31, which, when the locking pin is in locking position, seats upon the forward end of the longitudinal portion 17.

25 The normal position of the locking pin 30, due to the weights 27, and 29, which act as counter-balances for the shaft 25, is as shown in Fig. 2.

If it be desired to couple the cars, the link 30 11 engages the locking pin 30, will swing the same rearwardly, the slots 14 and 20, as well as the longitudinal slots in the sill and bottom will permit of such movement. After the link 11 clears a free end of the locking 35 pin, the weights 29 and 27 will cause said pin to ride itself, the latter will pass through the link and will be moved to the position shown in Fig. 2 and under such conditions the cars will be coupled.

40 When it is desired to uncouple the cars, the pin 30 is shifted rearwardly manually until the coupler link 11 is released.

Mounted in the brackets 22 and 23 is a rock shaft 25 having each end provided with 45 an opening, said openings being indicated at 26 and 27, and its central portion with an opening 28, the latter being disposed substantially at right angles with respect to the openings 26 and 27.

50 Mounted in each of the openings 26 and 27 is a counterbalance consisting of an arm 29, carrying on its upper end a globular weight 30. The lower end of the arm 29 has a transverse opening 31 through which extends a cotter pin 32 for adjustably connecting the weighted member to the shaft 25.

Extending through the opening 28 is a locking pin 33, which is offset at its upper end to provide a shoulder 34. The lower end 60 of the pin 33 is notched as at 35.

When the pin 33 is mounted in the shaft 25 it extends up through the slots 14 and 18 and also the alining slots in the sill 3.

The shoulder 34 overlaps the outer end of the longitudinal portion 17. The pin 33 also 65 extends through the coupler link 11 and acts as a means for coupling the two cars together.

Arranged below the bottom of the car 1, is a coil spring 36, which has its lower end 70 connected to a keeper 37 and its forward end engaging in the notch 35, as at 38. The spring 36 is disposed at an inclination and its function, in connection with the weighted members, is to maintain the locking pin 33 75 in a perpendicular position whereby the link 11, which is permanently carried by the car 2, will be coupled to the car 1.

Connected to the sill 4, as well as extending below said sill, is a casing 39 and arranged therein, between the sill 4 and said casing, is a pair of spring controlled buckers 40, which normally project, as at 41, beyond the sill 4.

The normal position of the locking pin 35 33, due to the weighted members and spring 36, is as shown in Fig. 2.

If it be desired to couple the cars, the link 11 engages the locking pin 33, and swings the same rearwardly. The slots 41 and 20, 90 as well as the longitudinal slot in the sill 3, will permit of such movement. After the link 11 clears the free end of the locking pin 33, the weighted members and spring 36, will cause said pin to ride itself, that is to 95 say assume a perpendicular position and as the locking pin 33 moves to perpendicular position it will pass through the link 11 and eventually assume the position shown in Fig. 2, under such conditions coupling the cars 100 together.

When it is desired to uncouple the cars, the locking shaft 25 is swung rearwardly manually, by engaging with either of the weighted members the coupler link is released and the cars can then be separated.

By providing the shaft 25 with openings 26 and 27, if a weighted member should become damaged, or the locking pin 33 broken, they can be conveniently removed and new 110 ones substituted.

What I claim is:

1. A coupler for pit cars comprising an upper and a lower draw head adapted to be secured to a car and providing a recess for a coupler link, said draw heads having alining slots, a spring controlled rock shaft adapted to be pivotally supported from the sill of the car and having a counter-weight at each end, and a locking pin projecting from said shaft and normally maintained in locking position by said weights and the controlling spring for said shank, said slots providing clearances for the pin when shifted to and from normal position.

2. A coupler for pit cars comprising the

combination with the front end of a draw bar, an upper draw bar having a portion spaced from said front end to provide the recess for a coupling link, said upper draw bar having longitudinally extending slots
5 alining with each other, of a locking pin extending through said slots and normally in locking position and capable of being shifted from locking position by a coupler link until cleared by said link, and a spring controlled
10 rock shaft pivotally connected with the

sill of the car and provided with counter-weights for automatically restoring said locking pin to locking position after being cleared by said link whereby the latter is 15 connected to the car.

In testimony wherein I affix my signature in the presence of two witnesses.

RALPH P. TOWARD.
